RESILIENTLY EXPANDED SCRAPER DEVICE
FOR REMOVING CARBON FROM VALVE
GUIDESWilliam H. Spang, Cleveland, Ohio, assignor to
St. Clair Machine Products Company, Cleve-
land, Ohio, a partnership

Application March 14, 1947, Serial No. 734,766

8 Claims. (Cl. 15—104.01)

1

This device relates, as indicated, to a device for removing carbon from valve guides, but has reference more particularly to a tool or device which has been especially designed to remove carbon deposits from the walls of the guides in which the stems of valves of internal combustion engines slide.

A primary object of the invention is to provide a device of the character described which is effective not only to break or loosen the carbon deposits on the walls of such guides, but also to scrape and remove the carbon deposits thus broken or loosened.

Another object of the invention is to provide a device of the character described having a novel roller for loosening or breaking the carbon deposits.

A further object of the invention is to provide a device of the character described having novel spring means for pressing the aforesaid roller against the wall of the guide.

A still further object of the invention is to provide a device of the character described, in which the aforesaid spring means can be moved in such a manner as to increase or decrease the degree of pressure exerted upon the wall of the guide by the roller, and in which the spring means is of such form or contour as to permit use of the device on valve guides of various diameters.

A still further object of the invention is to provide a device of the character described which consists of a minimum number of parts which are inexpensive to manufacture, and which can be quickly and easily assembled and cleaned.

Other objects and advantages of the invention will be apparent during the course of the following description.

In the accompanying drawings, forming a part of this specification, and in which like numerals are employed to designate like parts throughout the same,

Fig. 1 is a front elevational view of a device embodying the novel features of the invention;

Fig. 2 is a side elevational view of the device;

Fig. 3 is a cross-sectional view of the device, taken on the line 3—3 of Fig. 1, but showing the manner in which the device is used to remove carbon deposits from a valve guide;

Fig. 4 is an end elevational view, taken on the line 4—4 of Fig. 1, and

Fig. 5 is a cross-sectional view, taken on the line 5—5 of Fig. 1.

Referring more particularly to the drawings, it will be seen that the device for breaking and cleaning carbon comprises a stem consisting of

2

two parts 1 and 2, which are spaced axially from each other, and are rigidly interconnected by a shaft or pin 3, which is offset from the axis of the parts 1 and 2. The part 1 of the stem has rigidly secured to its upper end a knob or handle 4, having a knurled edge 5 to facilitate rotation or movement of the parts 1 and 2 in an axial direction.

The part 1 of the stem has a longitudinally-extending recess 6 in the periphery thereof, which extends the entire length of the part 1, and is increased in depth adjacent its lower end, to form an arcuate recess, as at 7.

The part 2 of the stem is similarly provided with a recess 8 in its periphery, which extends the entire length of the part 2, and is in alignment with the recess 6. The lower end of the recess 8 is increased in depth to provide an inclined cam surface 9, the function of which will be presently explained.

Slidably mounted on the stem 1, for movement along such stem, is a handle or knob 10 of considerably greater diameter than the handle or knob 4, and having a knurled periphery 11, which facilitates rotation of the handle as well as movement of the handle along the stem 1.

The handle or knob 10 has a radially-extending opening 12, in which the flange 13 of a carbon wiper element 14 is disposed. The element 14 is preferably made from spring steel of rectangular cross-section, and comprises an upper portion 15 which is disposed in the recess 6, which thus constitutes a track for longitudinal movement of the element 14, an intermediate portion 16 which is normally bowed outwardly, and an inclined lower end 17, which is disposed in the recess 8, which thus constitutes a track for longitudinal movement of the end 17. The portion 16 of the element 14 is provided with a radially-inwardly extending portion 18, of arcuate contour, the purpose of which will appear hereinafter.

Loosely mounted on the shaft or pin 3 for free rotation about such shaft, is a roller 19, having its peripheral surface 20 knurled, and its ends slightly tapered, as at 21 and 22. The diameter of the roller 19 is such that a portion thereof projects slightly beyond the peripheral surface of the stem parts 1 and 2, as clearly shown in Fig. 3.

Having thus described the construction of the device, its use or operation will now be briefly described.

The device is designed primarily to break and remove the carbon which becomes deposited on the inside or wall of the guides for the stems of

valves in internal combustion engines and the like. For this purpose, the parts 1 and 2 of the stem of the device are inserted into the valve stem guide, from which it is desired to remove the carbon deposit.

As these parts of the stem are thus inserted in the valve guide, the element 14 of the device is pressed radially-inwardly by the wall of the valve guide G, as shown in Fig. 3, thus causing the roller 19 to be resiliently pressed against the opposite side of the wall of the valve guide. Then, by a conjoint vertical and rotary movement of the stem parts 1 and 2 by means of the handle or knob 4, the projections formed by the knurling 20 of the roller 19 function to break the carbon on the wall of the valve stem guide, into small particles. These particles can then be scraped from said wall by rotation of the element 14 which functions as a scraper for this purpose, the rotation of such element being effected by rotation of the knob or handle 10. The element 14 thus functions both as a scraper, and as a means of resiliently maintaining the roller 19 in contact with the wall of the valve stem guide.

By movement of the element 14 up or down by means of the handle or knob 10, various portions thereof may be brought into contact with the wall of the valve guide, thereby increasing or decreasing the degree of pressure exerted upon the wall of the guide by the roller 19. This vertical adjustment of the element 19 is also designed to permit the device to accommodate itself to valve guides of different diameters. The degree of adjustment of compression is increased by virtue of the movement of the lower end 17 of the element 14 on the inclined cam surface 9 of the stem part 2. The tapered ends 21 and 22 of the roller 19 facilitate vertical movement of the roller in the valve guide.

It may be noted that the adjustment of the element 14 is controlled from the outside of the valve guide, close to the turning handle or knob 4. The portion 7 of the recess 6 is designed to receive the portion 18 of the element 14, at such time when the device is to be used in scraping carbon from valve guides whose wall diameter is only slightly greater than the diameter of the stem parts 1 and 2. The portion 18 of the element 14, when disposed in the portion 7 of the recess 6, as shown in Fig. 3, enables the stem 1, 2, to apply a torque to the element 14 at the central portion of the latter, thereby facilitating rotation of the element 14. It also prevents distortion of the element 14 during the use of the device.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

Having thus described my invention, I claim:

1. In a device of the character described, a handle, a stem extending from said handle and having a longitudinally-extending recess therein, a roller mounted for rotation about an axis parallel to the axis of said stem and having surface projections adapted to break carbon deposits on the walls of valve stem guides, a second handle mounted to slide along said stem, and a spring having one end attached to said last-named handle, a portion disposed in said recess, and an outwardly bowed portion adapted to coat with the wall of said guide to resiliently press said roller against the opposite wall of the guide.

2. A device, as defined in claim 1, in which said stem comprises axially-spaced portions, and said roller is rotatable about a shaft which interconnects the portions of said stem.

3. A device, as defined in claim 2, in which both parts of said stem have longitudinally-extending recesses, in alignment with each other and constituting said first-mentioned longitudinally-extending recess and said spring has one end thereof disposed in each of said recesses, whereby the spring is constrained to move in the track formed by said recesses.

4. A device, as defined in claim 3, in which one of said aligned recesses has an inclined surface forming a cam surface against which one end of said spring is adapted to bear, said spring end being movable along said cam surface, whereby the adjustment of compression of the spring is controlled.

5. In a device of the character described, a handle, a stem extending from said handle, a roller mounted for rotation about an axis parallel to the axis of said stem and having surface projections adapted to break carbon deposits on the walls of valve stem guides, and means for resiliently urging said roller into engagement with said wall, said means comprising a spring having sharp edges adapted to scrape the broken carbon from said wall as the stem is rotated, means for shifting said spring to a plurality of selected positions along said stem, and means responsive to said shifting movement to radially expand the spring, whereby to increase the pressure of said roller against said wall.

6. A device, as defined in claim 5, in which said stem has a longitudinally extending groove in the peripheral wall thereof, and said spring has a portion disposed in said groove.

7. In a device of the character described, a handle, a stem extending from said handle, a roller mounted for rotation about an axis parallel to the axis of said stem and having projections adapted to break carbon deposits on the walls of valve stem guides, means comprising a spring resiliently urging said roller into engagement with said wall, which spring also functions to scrape the broken carbon from said wall, said spring being movable to a plurality of positions axially along said stem, and means responsive to said axial movement to radially expand the spring, whereby to increase the pressure of said roller against said wall.

8. A device, as defined in claim 7, in which said stem has a recess therein, and said spring has a portion thereof disposed in said recess.
